UNITED STATES PATENT OFFICE.

HARRY WILSON AND ABNER Y. LEECH, JR., OF WASHINGTON, DISTRICT OF COLUMBIA, ASSIGNEES TO UNITED STATES ORDNANCE COMPANY, OF WASHINGTON, DISTRICT OF COLUMBIA, A CORPORATION OF VIRGINIA.

PERCUSSION-FUSE.

No. 829,361.

Specification of Letters Patent.

Patented Aug. 21, 1906.

Application filed June 10, 1905. Serial No. 264,590.

To all whom it may concern:

Be it known that we, HARRY WILSON and ABNER Y. LEECH, Jr., citizens of the United States, residing at Washington, in the District of Columbia, have invented certain new and useful Improvements in Percussion-Fuses, of which the following is a specification.

Our invention relates to that class of fuses for explosive projectiles in which the percussion element is released by centrifugal force, such as is due to the rotation of the projectile in flight when fired from a rifled gun.

In handling projectiles in which fuses are mounted the fuse may be rendered inoperative by a drop of the projectile upon a protruding object, such as a bolt-head, so that a contact is produced with the exposed portion of the fuse, such contact producing a longitudinal deformation of the fuse and a resulting undue disarrangement of the elements thereof, whereby an inoperative state of the fuse is produced either by premature explosion, premature arming, or by rendering same incapable of arming under service conditions. It is the object of our invention to provide means for preventing the rendering of the fuse inoperative from any of the before-mentioned causes as a result of the above-described deformation of the fuse.

Broadly, the object of our invention is to simplify and improve the structure and operation of percussion-fuses, to insure greater safety in handling the projectiles, and certainty in exploding the shell after it strikes the target.

With the above and other objects in view the invention consists in the details of construction and in the arrangement and combination of parts to be hereinafter more fully set forth and described.

In describing the invention in detail reference will be had to the accompanying drawings, which form part of this specification and wherein like characters of reference indicate corresponding parts in the several views, and in which—

Figure 1 is a partial longitudinal section of our improved fuse; Fig. 2, a section on the line *a a* of Fig. 1; Fig. 3, a view similar to Fig. 2, the guard being in its expanded or armed position; Fig. 4, a partial longitudinal section of a fragment of the fuse on the line *b b* of

Fig. 2, and Fig. 5 a transverse section of the safety-guard.

In the drawings, A represents the fuse-stock, which is provided with the shoulders A' and A² in its chamber. Secured in the fuse-stock with suitable threads and having its outer face registering with the shoulder A² is a primer-plug B. The inner face of the plug B is provided centrally with the projection B', which forms a seat for the primer B². A channel B³ leads from the primer-seat through the plug B for the purpose of conveying the primer-flash to the magazine formed in the forward end of the stock between the outer face of the primer-plug and a disk C, which closes the open end of the fuse-stock.

A firing-hammer D, provided with a firing-point D', is normally situated in the chamber of the fuse-stock between the rear wall of said chamber and the shoulder A'. A centrifugally-operated safety-guard is situated between the firing-hammer and the primer-plug and normally holds the firing-hammer against forward movement. Said safety-guard is formed of the segmental members E and E', which are normally held together, so that their straight surfaces abut, by means of the spring-actuated bolts E² and E³, the bolt E² being rigidly secured to the member E, while the bolt E³ is rigidly secured to the member E', both of said bolts protruding at right angles to the straight surface of the member to which they are rigidly secured. The member E is provided with an aperture E⁴, adapted to receive the bolt E³ of the member E', while said member E' is provided with a like aperture E⁵, adapted to receive the bolt E². The apertures E⁴ and E⁵ are counterbored, so as to form the shoulders E⁶ and E⁷, respectively. A spiral spring E⁸ is interposed between the head of the bolt E³ and the shoulder E⁶, and another spring E⁹ is interposed between the shoulder E⁷ and the head of the bolt E², the coaction of said springs E⁸ and E⁹ with the head of the bolt E³ and the shoulder E⁶ and with the head of the bolt E² and the shoulder E⁷ respectively serving to compress the members E and E', so that their straight surfaces abut. By the arrangement of the bolts E² and E³ on the opposite sides of the short axis of the guard any relative movement of the members E and E'

other than a transverse movement parallel to the transverse axis of the fuse is prevented. The members E and E' are recessed at the front and rear to form the flanges E¹⁰ E¹¹ and 5 E¹² E¹³, respectively. Recesses E¹⁴ and E¹⁵ are formed in the members E and E', respectively, and are adapted to register at their open ends when the guard is in its normal position to form a longitudinal aperture in 10 said guard which envelops the firing-point D'. Driving-pins B⁴ and B⁵ are rigidly secured to the primer-plug B and enter the recesses E¹⁶ and E¹⁷, respectively, which are formed in the forward end of the guard at the termina- 15 tion of its long axis, a part of each member of the guard being cut away to form said recesses. It will thus be obvious that were the guard mounted without engagement with a portion of the fuse which immediately par- 20 takes of the full rotation of the shell it would tend to remain at rest independent of said rotation, and the members E E' would fail to move transversely with the desired prompt- 25 ness. By the construction shown, however, the full rotation of the shell will be imparted at once to the members E E' and the engagement between the surfaces of the recesses E¹⁶ and E¹⁷ and the driving-pins B⁴ and B⁵, respectively, operating against the tendency 30 of the members to remain at rest will cause a prompt initial transverse movement of said members.

To obviate an undue disarrangement of the firing-hammer resulting from the deformation of the fuse by dropping same mounted in a projectile on a protruding object, we provide a lead plug D³, which is secured centrally in the rear of the firing-hammer in a suitable manner. Said plug is of a diameter 40 less than that of the firing-hammer and pro- trudes therefrom, so as to separate the rear end of the hammer and the rear wall of the fuse-chamber. It will be apparent, in view of the fact that the lead plug is of a greater 45 degree of softness than either the metal comprising the fuse-stock or the firing-hammer, that should a deformation of the fuse-stock take place from causes heretofore mentioned same will be without effect on the firing- 50 hammer, because of the interposition of the lead plug, which will readily mash and expand radially and prevent the transmission of the effect of such deformation to the firing-hammer or safety-guard.

55 It will be noted that while we have described and shown a particular means for preventing the transmission of the effect of the deformation of the fuse-stock to the firing-hammer we do not limit ourselves there- 60 to, as various other means may be employed for accomplishing this purpose without de- parting from the scope of our invention.

We claim—

1. In a non-pressure fuse the combination 65 of a casing having mounted in the chamber

thereof, a primer, a firing-hammer, securing means normally holding the firing-hammer in safe position and means permitting a longitudinal deformation of the casing without disarranging the elements of the fuse or de- 70stroying their function.

2. In a non-pressure fuse the combination 75 of a casing having mounted in the chamber thereof, a primer, a firing-hammer, securing means normally holding the firing-hammer in safe position and compressible means per- 80mitting a longitudinal deformation of the casing without disarranging the elements of the fuse or destroying their function.

3. In a non-pressure fuse the combination 85 of a casing having mounted in the chamber thereof, a primer, a firing-hammer, securing means normally holding the firing-hammer in safe position and a compressible member 90 permitting a longitudinal deformation of the fuse - casing without disarranging the ele- 95ments of the fuse or destroying their func- tion.

4. In a non-pressure fuse the combination 95 of a casing having mounted in the chamber thereof, a primer, a firing-hammer, securing means normally holding the firing-hammer in safe position and a compressible metal member permitting a longitudinal deforma- 100tion of the casing without disarranging the 105elements of the fuse or destroying their func- tion.

5. In a percussion-fuse the combination of 100 a casing having mounted in the chamber thereof, a primer, a firing-hammer, securing means operated independently of the pres- 105sure of the powder-gases normally locking the firing-hammer in safe position and compres- 110sible means permitting a longitudinal deforma- 115tion of the casing without disarranging the 120elements of the fuse or destroying their func- 125tion.

6. In a percussion-fuse the combination of 110 a casing having mounted in the chamber thereof, a primer, a firing-hammer, securing means operated independently of the pres- 115sure of the powder-gases normally locking the firing-hammer in safe position and means 120 permitting a longitudinal deformation of the 125casing without disarranging the elements of the fuse or destroying their function.

7. In a percussion-fuse the combination of 120 a casing having mounted in the chamber thereof, a primer, a firing-hammer, securing means operated independently of the pres- 125sure of the powder-gases normally locking the firing-hammer in safe position and a com- 130pressible member permitting a longitudinal deforma- 135tion of the casing without disarranging the elements of the fuse or destroying their func- 140tion.

8. In a percussion-fuse the combination of 130 a casing having mounted in the chamber thereof, a primer, a firing-hammer, securing means operated independently of the pres- 135sure of the powder-gases normally locking the firing-hammer in safe position and a com- 140pressible member permitting a longitudinal deforma- 145tion of the casing without disarranging the elements of the fuse or destroying their func- 150tion.

sure of the powder-gases normally locking the firing-hammer in safe position and a compressible metal member permitting a longitudinal deformation of the casing without disarranging the elements of the fuse or destroying their function.

9. In a percussion-fuse, the combination of a casing, a primer, a firing-hammer and a centrifugally-released safety-guard normally holding the firing-hammer in safe position, said safety-guard comprising segmental members each of which has a bolt rigidly secured thereto and loosely penetrating the other member and springs coacting with said bolts and members to move said members toward each other.

10. In a percussion-fuse, the combination of a casing, a primer, a firing-hammer and a centrifugally-released safety-guard normally holding the firing-hammer in safe position, said safety-guard comprising segmental members each of which has a bolt rigidly secured thereto and loosely penetrating the other member above and below the short axis of the guard respectively and springs coacting with said bolts and members to move said members toward each other.

11. In a percussion-fuse, the combination of a casing, a primer, a firing-hammer and a centrifugally-released safety-guard normally holding the firing-hammer in safe position, said safety-guard comprising segmental members normally held together by yielding connections situated above and below the short axis of the guard.

12. In a percussion-fuse, the combination of a casing, a primer, a firing-hammer and a centrifugally-released safety-guard normally holding the firing-hammer in safe position, said safety-guard comprising segmental mem-

bers, yielding connections above and below the short axis of the guard normally holding the members together and preventing any independent movement of the members other than a transverse movement in opposite directions parallel to the transverse axis of the fuse.

13. In a percussion-fuse, the combination of a casing, a plug carrying a primer, a firing-hammer, centrifugally-released securing means normally holding the firing-hammer in safe position and means carried by the primer-plug adapted to coact with the securing means after discharge to assist the unlocking of said securing means.

14. In a percussion-fuse the combination of a casing having mounted in the chamber thereof, a primer, a firing-hammer and a complete securing means normally holding the firing-hammer in safe position and means permitting a longitudinal deformation of the casing without disarranging any portion of the elements of the fuse or destroying their function.

15. In a percussion-fuse the combination of a casing having mounted in the chamber thereof, a primer, a firing-hammer and a complete securing means normally holding the firing-hammer in safe position and a compressible metal member permitting a longitudinal deformation of the casing without disarranging any portion of the elements of the fuse or destroying their function.

In testimony whereof we affix our signatures in presence of two witnesses.
